UNITED STATES PATENT OFFICE.

WILLIAM J. DYER AND THOMAS W. MAXEY, OF NEVADA, MISSOURI.

WEATHER-BOARD GAGE.

SPECIFICATION forming part of Letters Patent No. 307,927, dated November 11, 1884.

Application filed September 29, 1884. (No model.)

To all whom it may concern:

Be it known that we, WILLIAM J. DYER and THOMAS W. MAXEY, citizens of the United States, residing at Nevada, in the county of 5 Vernon and State of Missouri, have invented certain new and useful Improvements in Weather-Board Gages, of which the following is a description.

This invention relates to that class of devices used by carpenters in spacing weather-boards while nailing them on to the side of a house; and its object is to hold the board exactly in its proper relation to the previously-nailed board while the board is being scribed 15 for sawing to fit its place, and again when it has been fitted to hold it in the same position for nailing.

To this end our invention consists in the construction and combination of parts forming 20 a weather-board gage, hereinafter described and claimed, reference being had to the accompanying drawings, in which—

Figure 1 is a vertical section of a portion of the side of a house, showing our invention in 25 side elevation in use; and Fig. 2 is a front view of our invention.

A represents the body of our gage, which is usually made of wood, about eight or ten inches long and slotted, as at L.

30 B is a spur to be driven into a stud, C, of the house to hold the device in place.

D is a spring connecting the spur with the body and acting to press the body firmly against the house, yet permitting the body to be raised 35 away from the house enough to allow a weather-board to be pushed up under it. To assist this operation the lower end of the body is wedge-shaped at E.

F is the shoulder upon which the weather- 40 board is to be held in place while nailing, &c.

G is a pin, which is the gage of distance 45 between the weather-boards. This pin is supported on a spring, H, which holds the pin drawn into the slot L in the body, but which will permit the pin to project from the under side of the body, as shown in dotted lines, when in use.

J is a set-screw in the slot L, holding the 50 spring H and pin G to the body A. This set-screw is movable along the slot, and may be bound tight at any point therein to hold the pin at a distance from the shoulder F corre-

sponding to the space between the lower edges of the weather-boards. Along the side of the body, at K, are marked spaces showing 55 inches and fractions thereof, measured from the shoulder F, to assist in setting the gage-pin.

In use, the gage-pin G is first set at the desired point and fixed by the set-screw J. Two 60 of the devices are placed against the weather-board already nailed on, with the gage-pins at the lower edge of the board; then the spurs B are driven by hammer blows into the studs. Now another weather-board is pushed up under the two gages to rest on their shoulders F. Then this board is scribed to be cut to fit the window or door casings, &c., and taken out 65 from under the gages to be so cut. Then the board is returned to place on the shoulders F 70 and nailed to the house. Now the gages must be removed by withdrawing the spurs and replaced relative to the last board nailed on. By this means one person may do the work of 75 two working without any such aids, do it more accurately, and work as well on a windy day as in still weather. By attaching the spring D to the outer face of the body A the upper end thereof is left free to serve as the shoulder F, described.

What we claim as our invention, and desire 80 to secure by Letters Patent, is—

1. The combination, with the slotted body A, of the spring D, secured to the outer face thereof, leaving the end F free to serve as a shoulder, the spur B in the free end of spring D, the pin G in the slot L, the spring H, carrying the pin G, and the set-screw J, holding the spring H and adjustable along the slot L, as shown and described. 90

2. The combination, with the spring D, having the spur B at its upper end, of the body A, secured at one of its sides to the spring D, leaving the end F of the body free to serve as a shoulder, the gage-pin J, and means, substantially as described, for adjustably securing it to the body A, the said body being wedge-shaped at its lower end, as shown and described. 95
